ART OF MOLDING

Donald J. Campbell, Spring Lake Township, Ottawa County, Mich., assignor to Campbell, Wyant & Cannon Foundry Company, Muskegon, Mich., a corporation of Michigan

Application August 17, 1935, Serial No. 36,679

4 Claims. (Cl. 22—129)

This invention relates to the art of molding, and is concerned primarily with the molding and casting of elongated articles which may be of an irregular shape, for example, crank shafts, or 5 may be like an integrally cast internal combustion engine cylinder block. In such cases there are used baked sand molds or cores. In the casting of crank shafts, one way in which the same have been cast by me is to provide a baked sand 10 mold. In the casting of cylinder blocks, elongated baked sand cores are used, particularly in blocks for the so-called V-engines.

With articles of the nature mentioned, which 15 are two examples only of many different types 15 of elongated and more or less irregularly shaped articles cast from cast iron, when the molten iron from which they are cast solidifies in the mold, there is a shrinkage of the iron which shows its greatest effects in the direction of the greatest dimension of the casting made. This 20 shrinkage in an elongated article like a crank shaft or in a long engine block, is in the length of the casting.

Baked sand molds or baked sand cores are 25 resistant against the movement of the casting which takes place because of such shrinkage. While the iron burns the adjacent portions of the sand cores or molds where it strikes it to a slight degree, the body of core does not yield readily 30 and easily.

Therefore, in a great many cases when the casting shrinks and engages against the baked sand mold or core, with the resistance which the core has against the casting moving because of 35 such shrinkage, there are strains set up in the casting which frequently manifest themselves in the finished castings in checks, cracks or other imperfections.

The present invention is directed to a very simple, practical, economical and particularly effective mold or core improvement whereby all such detrimental effects which have previously occurred because of the hard and more or less unyielding nature of the core sand used are entirely 45 eliminated and the shrinkage of the casting may take place freely and not be subjected to the resistance of the baked core sand material, as has been previously the case. There is an elimination of defects in the finished casting 50 which have heretofore frequently occurred because of the resistance to shrinkage coming from the relatively unyielding nature of the baked core sands or molds.

For an understanding of the invention, refer-

ence may be had to the following description, taken in connection with the accompanying drawings, in which,

Fig. 1 is a horizontal section through a baked core sand mold for casting a crank shaft, the 5 mold incorporating my invention therein.

Fig. 2 is a transverse section substantially on the plane of line 2—2 of Fig. 1.

Fig. 3 is an elevation of the readily compressible member or plate, several of which are used 10 in the length of the mold as shown in Figs. 1 and 2.

Figs. 4 and 5 are elevations of two alternative constructions of collapsible or compressible plates, such as are shown in elevation in Fig. 3. 15

Fig. 6 is a transverse section through an internal combustion engine casting with the elongated cores such as are used in casting the same, in place as they are used.

Fig. 7 is a plan and section of the structure 20 shown in Fig. 6, the section being on the plane of broken line 7—7 of Fig. 6.

Fig. 8 is a central longitudinal vertical section through the engine block casting and two large longitudinal cores which are used, and 25

Figs. 9 and 10 are elevations, respectively, of the collapsible plates used in the upper and lower longitudinal cores in casting the engine block, a plurality of such collapsible plates being within the cores transversely thereof and in spaced 30 apart relation to each other.

Like reference characters refer to like parts in the different figures of the drawings.

The engine block casting 1, see Figs. 6 and 8, is of a type such as is used in providing a multiple cylinder internal combustion engine of the V-type. The crank shaft is of a conventional design, having a plurality of cranks 3 with adjacent integral flanks 4 connecting the same all as fully shown in Figs. 2. In the application of 40 my invention to the casting of a crank shaft, the mold drag and cope 5 (Figs. 1 and 2) are made from core sand and baked in an oven so as to have the rigidity of baked sand cores. The mold cavities are of a shape such that when filled with molten iron the crank shaft is produced. There is in addition a cavity in the mold at one end of the crank shaft mold cavities and communicating therewith which fills with melted iron when the pouring takes place. This is shown at 50 6 in Fig. 1. The usual runner gates 7 and 8 for carrying the iron to the mold cavities are provided. The mold is filled with molten iron when in a horizontal position and then turned 55 upright to a substantially vertical position so

as to bring the iron at 6 at the upper end of the casting to be made so as to feed molten iron to the casting as it cools and shrinks.

In the making of the drag and cope 5 for casting crank shafts, a plurality of transverse plates 9 are used so located as to lie between flank portions 4 as shown in Fig. 1. Inasmuch as the crank shaft shrinks from each end inwardly toward the central portion, there will be 10 more of these transverse plates 9 toward the ends of the crank shaft than at the center. The plates 9 are notched, for example, at 10 and 11, so as not to enter the mold cavities or the gate at 1.

It is evident from a reference to Figs. 1 and 15 2 that the plates 9 shown are nearly of an area equal to the transverse section of the drag and the cope in which they are located, there being however sufficient sand around the edges of the plates 9 that said plates are completely embedded 20 and enclosed within the mold.

When the iron is poured into the mold and shrinkage takes place the resistance which previously occurred to such longitudinal movement of the end portions of the crank inwardly toward 25 the center is now removed, the plates 9 collapsing or crushing in the direction of their thickness, that is, between their sides. These plates 9, as shown in Figs. 4 and 5, preferably consist of two spaced apart sides 12 of paper with a corrugated intermediate section 13 between the same, or there may be any other suitable material between the two sheets 12, such as that indicated at 14 in Fig. 5, which may be loose easily compressible fiber.

35 In practice what has been used has been well known corrugated paper board. The thickness of the plates 9, if a single one is used, preferably is about one-quarter of an inch, but two thicknesses of ordinary one-eighth of an inch corrugated paper board may be used satisfactorily. The pressure against the sides of the plates 9 crushes and collapses the same without any fear of setting up a resisting force sufficient to affect the casting.

45 In connection with the casting of a V-engine block, such as shown in Figs. 6, 7 and 8, there is an elongated core 16 which lies between the cylinder portions 15 and which, when the molten iron is poured, lies between the ends 17 of the 50 casting made. The longitudinal parts of the casting, indicated at 18 and 20 in Figs. 7 and 8, shrink and tend to draw the ends of the casting toward each other. A second longitudinal core 19 is located in the lower part and below the 55 ends of the cylinder portions 15 of the casting and this likewise lies lengthwise between the ends of the casting made. Therefore, the longitudinal shrinking tending to draw the ends of the casting toward each other necessitates pressing against the ends of the cores 16 and 19, which being of baked sand resist such pressure. The attempted movement of the ends of the casting inwardly toward each other has resulted in defects in the casting using solid cores.

60 65 With my invention, a plurality of transverse plates 9a in the upper core 16, and of 9b in the lower core 19, are used in spaced apart relation

to each other, the plates being shaped in accordance with the transverse section of the cores, as shown in Figs. 9 and 10, and nearly as large as the cross sectional areas of the cores. The same crushing of these plates 9a and 9b, because of the end pressure on the cores at 16 and 19, takes place, relieving strains in the casting and greatly aiding in the production of good castings.

The invention described is one of great practical merit. It is very simple, it is relatively inexpensive insofar as additional mold cost is concerned. The compressible collapsible plates serve to hold the mold or core in which used securely to its desired shape, compressing and collapsing only under the forces placed upon the mold or core by the shrinking of the iron.

It is, of course, to be understood that this transverse embedding of a paper board collapsible plate, or one of an equivalent nature for the same purpose, may be used in any core at any place where the shrinkage of the iron causes the same to press against opposite sides or ends of the core where the core resists the shrinkage which inevitably takes place when molten iron solidifies. Likewise molds made of core sand, one of which has been described with respect to the casting of a crank shaft, may utilize the locating of compressible plates like those described, made of corrugated paper board, transversely of the direction in which the pressure comes when the casting collapses so as to yield under the pressure of the shrinking casting.

The invention accordingly is not to be limited to the particular disclosures made or to the particular articles illustrated as being shown, but is 35 to be considered comprehensive of all structures coming within the scope of the claims appended hereto which define the invention.

I claim:

1. In a mold, an elongated mold element of 40 baked core sand, and a plurality of spaced apart plates of corrugated paper board located transversely of the mold in spaced apart relation to each other and completely embedded within the mold member and having dimensions approaching but somewhat less in all directions than the corresponding dimensions of the mold member in which positioned.

2. An elongated baked core sand mold having a member of paper board of the general outline 50 of the mold but smaller in area than the cross section of the mold disposed transversely of and within the baked sand mold material.

3. In the art of molding, a mold member of 55 baked sand having a plurality of spaced apart plates in said mold transversely thereof, each of said plates comprising a compressible layer of corrugated paper board crushable under pressure conditions existing during the molding operation, said plates being compressible and collapsible in the direction of their thickness, as and for the purposes specified.

4. A combination of elements as set forth in claim 3 in which said plates are spaced more closely at the end portions of the mold member.

DONALD J. CAMPBELL.
